UNITED STATES PATENT OFFICE.

CLIFFORD S. THOMAS, OF GORHAM, MAINE.

LIGHTING FIXTURE.

1,413,242.

Specification of Letters Patent. Patented Apr. 18, 1922.

Application filed August 28, 1920. Serial No. 406,569.

To all whom it may concern:

Be it known that I, CLIFFORD S. THOMAS, a citizen of the United States, residing at Gorham, in the county of Cumberland and 5 State of Maine, have invented certain new and useful Improvements in Lighting Fixtures, of which the following is a specification.

My invention relates to lighting fixtures 10 and is especially applicable to lighting fixtures upon articles of furniture designed to illuminate a mirror thereon, although my invention is not confined thereto but is useful in other relations and for other purposes.

15 One object of my invention, among others, is to produce a lighting fixture, or a pair of such fixtures, as an article of manufacture separate from the article upon which it is to be attached or which is to be illuminated, 20 and of a structure adapted for attachment to articles of various conformations.

Another object of my invention is to produce such a fixture and of such a structure 25 that it can readily be attached for permanent use to the article to be illuminated or detached at will.

Other objects of my invention will appear 30 from a detailed description thereof later to be given.

35 In the illustrative embodiment of my invention hereinafter referred to, I have selected the article of furniture known as a dressing table, having a centrally disposed mirror thereon as the article to which my invention in lighting fixtures is applied. This is to be understood, however, as illustrative of but one of its uses.

While my invention is capable of embodiment in many different forms, for the purposes of illustration I have shown only one 40 form of the same in the accompanying drawings, in which—

Figure 1 is a front elevation of the upper portion of the dressing table, including the 45 top, side arms and mirror, and with a pair of my lighting fixtures attached;

Fig. 2 is a rear elevation of the same;

Fig. 3 is a perspective view of one of my lighting fixtures unattached;

50 Fig. 4 is an end elevation of the jointed attaching plate with a portion of the lamp-supporting arm secured thereto.

The dressing table shown is of the usual type, comprising a table top 1 with side arms 55 2 arising therefrom to support a mirror 3

therebetween upon pivot pins 4 in the usual manner.

My improved lighting fixture comprises a bracket having, in the illustrative embodiment, a flat, jointed attaching plate comprising supporting arms 5 and 6 hinged together as at 7 so as to provide an attaching and supporting plate made up of two parts adjustable to any desired angle relative to one another. The hinge shown in the illustrative embodiment is of the usual type found in carpenters' rules, comprising a groove in the end of one of the articulating members and a tongue in the other with a hinge pin inserted through the articulating 60 parts so as to provide flush surfaces across the two arms.

Screw holes are provided in the arms referred to through which screws are inserted, as indicated at 8, for the attachment of the 65 supporting plate to the rear side of the arm or standard of the mirror.

The attaching plate after adjustment and attachment, as indicated to the rear of the mirror arm or standard, is designed for the 70 support of the lamp-bearing arm, which arm comprises a part attached to the attaching or supporting plate, a portion curved therefrom to clear the mirror arm and extending to the front of the dressing table and a 75 terminal upright lamp-bearing portion.

In the illustrative embodiment of the invention, the lower arm 6 of the attaching plate is attached in vertical position and the upper arm 5 at substantially the angle to the 80 vertical subtended by the mirror standard, and to the rear flat surface of the lower arm of the attaching plate, as shown in Fig. 2, is secured in any desired manner, as by soldering or welding, an elbow piece 9. This elbow 85 piece 9, in the illustrative embodiment of the invention, is formed of an elbow section of a pipe of the size and kind customarily used in conveying illuminating gas in houses for domestic lighting and having 90 screw-threaded ends or nipples. A second elbow piece 10 of like character screw-threaded to the first-mentioned elbow piece 95 provides the outwardly curved portion clearing the side arm of the mirror. Into the 100 forwardly extending end of this elbow piece 10, as shown in Fig. 1, is screw-threaded a short section of gas pipe 11, which section of pipe 11 extends in a horizontal plane to a 105 point in advance of the front surface of the 110

mirror, as shown. To this section 11 is screw-threaded a third elbow piece 12, the upwardly extending nipple of which forms the lamp-bearing portion of the bracket.

5 In the illustrative embodiment two such brackets are shown, a right and a left. Also in the illustrative embodiment of the invention, electric lamps of the usual type comprising a bulb 13 and a socket 14, are 10 shown, the socket being screw-threaded into the upwardly extending nipple of the elbow section 12 and held firmly in place by a nut 15.

15 Where electric lamps are used, the wires for the lamp sockets may be threaded through the hollow pipe sections, and the wires 16 are so shown in the illustrative embodiment.

20 Where it is desired to use illuminating gas, the hollow pipe sections function in the customary manner as gas conveyors, and the electric lamp bulbs and sockets are replaced by the usual gas bracket, including the gas jet, screw-threaded into the terminal section 25 of the gas pipe as is customary.

30 From the structure described, it is obvious that my lighting fixture can be applied to articles of various conformations. For example, where the fixture is to be applied to dressing tables, as in the illustrative application, and where, as is well known, the mirror supporting arms of different designs of dressing tables vary in the angle they make with the vertical, the hinged arms 5 and 6 35 can be adjusted to the angle corresponding to that subtended by the arms of the particular dressing table to which the fixture is to be applied, and thereafter the supporting plate, comprising the arms 5 and 6, screwed 40 into place. It is also apparent that the fixture can be as readily removed when desired.

45 While I have described my invention above in detail, I wish it to be understood that many changes may be made therein without departing from the spirit of the same.

I claim:

1. As an article of manufacture, a lighting fixture having an attaching plate comprised of a plurality of parts adjustable to varying angles relative to one another and a lamp-supporting portion extending rigidly from one face of said plate in a plane parallel to said plate and beyond an edge thereof and thereafter at an angle to the plane of said plate to a point beyond the opposite 55 face thereof.

2. As an article of manufacture, a lighting fixture having an attaching plate comprised of a plurality of parts adjustable to varying angles relative to one another and an arm 60 rigidly secured to one of said parts on one face of said plate and having a terminal portion for the support of a lamp or other source of illumination parallel with said part and beyond the plane of the opposite face 65 of said plate.

3. As an article of manufacture, a lighting fixture having a jointed attaching plate comprised of a plurality of parts relatively movable to varying angles one with another and a hollow arm secured at one end to one face of said attaching plate and having an angular offset portion clearing an edge of said attaching plate and a lamp-bearing terminal extending beyond the opposite face of said 70 attaching plate.

4. As an article of manufacture, a lighting fixture having an attaching plate comprised of a plurality of parts adjustable to varying angles relative to one another in the plane 80 of said plate and a lamp-supporting portion extending rigidly from one face of said plate and thereafter transversely to the plane of said plate to a point beyond the plane of the opposite face of said plate.

85 In testimony that I claim the foregoing, I have hereunto set my hand this 5th day of August, 1920.

CLIFFORD S. THOMAS.
